CLAIM

The ornamental design for a dispenser, as shown and described.

DESCRIPTION

FIG. 1 is an isometric view of a first embodiment of a dispenser according to the present invention; FIG. 2 is a top plan view of the dispenser illustrated in FIG. 1;

FIG. 3 is a front view of the dispenser illustrated in FIG. 1, the rear view being the mirror image thereof;

FIG. 4 is a left side view of the dispenser illustrated in FIG. 1, the right side view being the mirror image thereof;

FIG. 5 is a bottom plan view of the dispenser illustrated in FIG. 1;

FIG. 6 is an isometric view of a second embodiment of a dispenser according to the present invention;

FIG. 7 is a top plan view of the dispenser illustrated in FIG. 6;

FIG. 8 is a front view of the dispenser illustrated in FIG. 6, the rear view being the mirror image thereof;

FIG. 9 is a left side view of the dispenser illustrated in FIG. 6, the right side being the mirror image thereof;

FIG. 10 is a bottom plan view of the dispenser illustrated in FIG. 6;

FIG. 11 is an isometric view of a third embodiment of a dispenser according to the present invention;

FIG. 12 is a top plan view of the dispenser illustrated in FIG. 11;

FIG. 13 is a front view of the dispenser illustrated in FIG. 11, the rear view being the mirror image thereof;

FIG. 14 is a left side view of the dispenser illustrated in FIG. 11, the right side view being the mirror image thereof; and,

FIG. 15 is a bottom plan view of the dispenser illustrated in FIG. 11.
